HUDSON A. TEDMAN, OF GALESBURG, ILLINOIS, ASSIGNOR TO WINSLOW BOILER & ENGINEERING COMPANY, OF CHICAGO, ILLINOIS, A CORPORATION OF ILLINOIS.

SAFETY DEVICE FOR OIL-BURNING SYSTEMS.

Application filed June 21, 1921, Serial No. 479,223. Renewed March 15, 1923.

To all whom it may concern:

Be it known that I, HUDSON A. TEDMAN, a citizen of the United States, residing at Galesburg, in the county of Knox and State 5 of Illinois, having invented certain new and useful Improvements in Safety Devices for Oil-Burning Systems, do hereby declare that the following is a full, clear, and exact description of the same, reference being had 10 to the accompanying drawings.

The invention relates to certain new and useful improvements in safety-devices for oil burning systems, and its primary object is to provide an improved apparatus for 15 safely producing a periodical flame from a mixture of air and atomized oil, and particularly means for automatically stopping the motor and the supply of fuel-oil to the burner in case the system fails to function, 20 as for example if the oil is not sufficiently atomized or the air supply is insufficient to provide a combustible mixture of oil and air, or if the ignition device does not ignite the fuel mixture.

25 In oil burning systems or plants using heavy grades of fuel-oil the oil is atomized and mixed with a supply of air to form the combustible mixture, which then is ignited by a suitable pilot light or electric spark, 30 and as these systems are usually intermittent in their heating action on the steam-generator or boiler, operating in accordance with the varying thermal conditions in the device being heated they are usually provided with means for periodically starting 35 and stopping the motor that drives the blower to supply the combustion air to the burner. However, these means do not otherwise control the system and if there is a failure to produce or ignite the combustible mixture in the burner when an operative period occurs the fuel-oil continues to flow to the burner.

40 My invention provides improved means for automatically stopping the motor and flow of fuel-oil to the burner after a small quantity of this oil has passed to the burner under any condition that fails to produce a combustible mixture or ignite it, and so 45 prevents the accidental accumulation or waste of oil and the danger of explosion of the vapor arising from its natural vaporization in the restricted area of the fire-box or boiler-room.

50 In the accompanying drawings Fig. 1 is

a side elevation of a device embodying the features of my invention with a detail sectional view of a suitable fire-pot or burner; Fig. 2 is a detail view of the automatic trip-device, and Fig. 3 is a detail sectional view 60 of a form of electro-magnetic valve that may be employed.

In the drawings the reference numeral 1 indicates a combustion-chamber or fire-pot of suitable size and shape to conform to the 65 design of the associated steam-boiler, and to which fuel-oil is supplied by a fuel-pipe 2. A low-pressure blower 3 is mounted on a base-plate 4 and is provided with an air tube 5 which is connected at its outlet to 70 the fire-pot to furnish the combustion-supporting air; the air-tube preferably is divided at its outlet into two branches or conduits arranged tangentially to the interior of the fire-pot to deliver air to the pot in 75 two lateral streams on opposite sides of the nozzle 6 of the fuel-pipe 2. The conduits are suitably connected to the fire-pot, and these parts are provided with supports 7 and 8.

80 The blower is driven by an electric motor 9, which is mounted on the base 4 and is connected in an electric circuit 10 having any suitable source of current, and the circuit may be controlled to start and stop 85 the motor by any usual device such as the switch S, which may be operated by hand or any suitable means operating in accordance with varying thermal conditions in the device being heated. When fuel-oil is 90 supplied to the fire-pot through the pipe 2 and the motor is operated the blower or fan 3 delivers a sufficient quantity of air through the tube 5 to mix with the oil to form a readily combustible mixture and ensure 95 perfect combustion of the fuel so formed. The oil is discharged into the fire-pot from the nozzle 6 and preferably falls upon an inclined distributing and vaporizing plate 11 located near the bottom of the 100 pot by which it is broken up and atomized. The vaporized oil mixes with the inflowing air to form a fuel mixture which is readily ignited by a gas-burner 12 which is located under the plate 11 and is connected to a 105 suitable source of gas-supply by a pipe 13. The distributor plate is preheated by the lighting flame so that the initial oil falling on it is more quickly and thoroughly vaporized to accelerate its mixture with the air 110

UNITED STATES PATENT OFFICE.

ARTHUR F. LINSNER, OF ASTORIA, NEW YORK, ASSIGNOR TO NEW YORK BLUE PRINT PAPER COMPANY, A CORPORATION OF NEW YORK.

PARALLEL ATTACHMENT FOR DRAWING BOARDS.

Application filed September 14, 1920. Serial No. 410,116.

To all whom it may concern:

Be it known that I, ARTHUR F. LINSNER, a citizen of the United States, and resident of Astoria, in the county of Queens and State of New York, have invented certain new and useful Improvements in Parallel Attachments for Drawing Boards, of which the following is a specification.

This invention relates to improvements in parallel attachments for drawing boards. The object of the invention is to provide a generally improved parallel attachment adapted to be manufactured at low cost and easily and quickly attached to the drawing board. Another object of the invention is to provide a parallel attachment adapted to be used with a drawing board of greater length than the straight edge used in the attachment. With the above and other objects in view the invention is embodied in an attachment comprising such parts, elements and arrangements thereof as are hereinafter set forth while reference is had to the accompanying drawings in which, Fig. 1 is a plan view of a drawing board equipped with the attachment.

Fig. 2 is a plan view of the pulley bracket attached to the left hand end of the straight edge.

Fig. 3 is a view of Figure 2 looking in the direction of arrow 3 in said figure.

Fig. 4 is a side view of the pulley bracket. Fig. 5 is a plan view of the right hand bracket on the straight edge.

Fig. 6 is a view of Figure 5 looking in the direction of arrow 6 in Figure 5.

Fig. 7 is a side view of the left hand bracket.

Fig. 8 is a plan view of the locking means for the cord which operates the straight edge.

Fig. 9 is a side view thereof showing the locking means closed.

Fig. 10 is a side view showing the locking means open.

Referring to Figure 1 the reference numeral 1 denotes the drawing board. To the latter is suitably secured four brackets marked 2, 3, 4 and 5 respectively. 6 is the straight edge which may be of any suitable construction and is provided with two parallel grooves 7 and 8 running the length of the straight edge. On the left hand end the straight edge is provided with a pulley bracket 9 which is bent in the form

of a Z. One arm carries the double pulley 10, the other arm is secured to the straight edge 6 while the intermediate or vertical portion 11 is adapted to slide along the edge 12 of the drawing board 1.

The other or right hand end of the straight edge carries a bracket 13 having two rollers 14 and 15. The bottom 16 of the bracket 13 is flush with the drawing boards' upper surface. The brackets may conveniently be attached with screws 17 as shown.

The brackets are mounted on the straight edge so that the vertical portions 11 and 18 respectively of the left and right hand brackets lie close to the ends of straight edge and the said vertical portions of the brackets are further apertured as at 19, 20 and 21, 22 as indicated in Figures 2 and 5.

To the upper edge 23 of the drawing board and preferably central thereof is secured a locking means 25 comprising a plate 26 screwed fast to the drawing board and which plate carries a spring 27 adapted to be closed down upon the plate 26 by means of a pivoted cam 28 operable by a lever 29. The spring has a hole or aperture at 30.

31 denotes a cord which is secured at its one end 35 to the bracket 2 and thence passes around the pulley 10, through aperture 20 in the bracket 9, thence through groove 7, aperture 22, around roller 14, through an eye in bracket 4, through the locking device by passing between the spring 27 and the plate 26, thence upward through the hole 30 in the spring, thence through an eye in bracket 3, thence again around the pulley 10, through hole 19, through groove 8, through hole 21 in bracket 13, thence around roller 15 and the other free end 40 is secured to bracket 5.

In using the attachment it is placed on the drawing board as shown in Figure 1 and bracket 9 is placed with its portion 11 against the side 12 of the drawing board thus placing the straight edge at ninety degrees to the said edge 12 and thereafter the cord is pulled tight and tied. When the lever 29 of the locking means 25 is moved down the cam 28 presses the spring 27 firmly down and the cord is then securely clamped between said spring and the plate 26 and the cord cannot move.

Thus the straight edge remains securely in its position at ninety degrees to the side

12 of the drawing board and may be moved up or down without changing its position relative to said edge 12. Any accidental push at either end of the straight edge 5 which would tend to bring it out of position is firmly resisted by the cord. The cord portions in the grooves 6 and 7 pull against each other.

If it is desired to use the straight edge 10 in any other position as for instance that shown at 50 in dotted lines, the lock at 25 is unlocked, the straight edge shifted to the desired position after which the lock is locked and the straight edge may then be 15 used in the new position.

One particular advantage of the foregoing arrangement resides in the fact that the cord is not crossed upon itself hence wears longer. Also that the cords are underneath and in the straight edge, hence are not in the way and present no obstacle to the user of the board. It is a particular and important feature of this invention, that the cords rest and operate in open 20 grooves. Heretofore it has been proposed to construct parallel attachments in which the cords pass through closed grooves or channels in the straight edge. In such such cases, when the cords break or wear 25 out, it is necessary to entirely disassemble the straight edge in order to provide new cords. This frequently causes breakage of the straight edge, besides being expensive and involving work, which can only be 30 done by skilled labor. With this invention, however, the draftsman himself can easily and quickly repair a broken cord.

Again, Figure 7 shows that the board may extend to the right beyond the bracket 40 13 as shown in dotted lines at 60 in which case the brackets 4 and 5 may be slightly raised if desired to permit the right end cord portions to pass above the drawing board.

45 It will further be understood that while the invention is shown in its preferred form, nevertheless changes and modifica-

tions may be made in the detailed construction without departing from the spirit of the invention or the scope of the appended 50 claim.

I claim:

The combination with a drawing board, of a parallel attachment therefor comprising a straight edge provided with two 55 parallel longitudinally extending open grooves in the under surface of said straight edge, means permitting parallel movement of said straight edge over the face of the drawing board consisting of a plurality of 60 apertured corner brackets secured to the four corners of the said drawing board, a guide bracket secured to the one end of the said straight edge, said bracket having a depending vertical portion adapted to slide 65 against the one side of the drawing board, said bracket being further provided with a lateral extension below the plane of the straight edge, a double grooved pulley mounted above said lateral extension, a second 70 bracket secured to the opposite end of the straight edge, said second bracket having a lateral extension flush with the lower surface of the straight edge, two separate single pulleys secured above said second 75 lateral extension, a single cable having one of its free ends secured to one of the said corner brackets, said cable then passing around the said double pulley in one of its grooves, thence through one of the said 80 open grooves in the straight edge to one of the said single pulleys, thence around the drawing board and through two of the said corner brackets, thence back to and around the said double pulley in the other groove 85 thereof, thence through the second open groove in the straight edge, thence around the second of the two single pulleys aforesaid, thence back to the fourth of the said corner brackets, where the other free end 90 of the cable is secured, and locking means for said cable secured to the upper side of the said drawing board.

ARTHUR F. LINSNER.
